WINDOW AND STORE SASH

Filed March 4, 1931

UNITED STATES PATENT OFFICE

1,924,694

WINDOW AND STORE SASH

Lawrence Michaels, Covington, Ky.

Application March 4, 1931. Serial No. 520,046

7 Claims. (Cl. 20—56.4)

My invention relates to metal window sash or store front sash adapted to support large and heavy panes or plates of glass. One of its objects is to provide an improved sash comprising a rectangular sash or frame provided with supports for a plate of glass and with a plurality of glass clamping jaw members adapted to form an outside finish and to retain the glass in position relative to the sash. Another object is to provide an improved sash or frame relative to which clamping jaws and jaw tensioning members and glass supporting members are adjustably supported. Another object is to provide an improved sash adapted to receive the glass from one side and to have a series of glass clamping jaw members applied over the edges of the glass after the glass has been seated in the sash. Another object is to provide an improved metal sash in which the glass is adapted to be applied from one side and a series of independent clamping jaw members applied detachably and removably to facilitate removal and replacement of the glass if required, and adapted to uniformly clamp the glass in place with a sufficient degree of resiliency to avoid danger of fracture of the glass. My invention also comprises certain details of form and arrangement, and combination of components all of which will be fully set forth in the description of the accompanying drawing, in which:

Fig. 1 is a plan view of a window sash or store front sash embodying my improvements.

Fig. 2 is a vertical section through the same taken on line 2—2 of Fig. 1.

Fig. 3 is a horizontal cross-sectional view of a sash of the invention.

Fig. 4 is a perspective view of a short section of one of the clamping jaw bars detached.

Fig. 5 is a perspective view of a short detached section of one of the bars from which the sash frame is constructed.

Fig. 6 is a perspective view of one of the clamping jaw engaging levers detached.

Fig. 7 is a perspective view of one of the glass supporting members detached.

Fig. 8 is an enlarged view showing the construction at the right-hand side of Fig. 3.

Difficulty has been experienced heretofore in providing sashes adapted to support large and heavy glass plates with satisfaction. Also in providing for conveniently placing the glass in the sash or frame, and in removing or replacing the glass if necessary. Also in holding the glass firmly in the sash without liability to fracture the glass. My improved sash and glass mounting

apparatus obviate these several difficulties, and provide an improved sash and means of reliably supporting the glass therein, and conveniently removing and replacing the glass. I am also enabled to construct high grade sash members 60 from stock bars of extruded metal at relatively low cost in material and labor.

The accompanying drawing illustrates one embodiment of my invention in which 15 represents a pane of glass and 16 represents an open rectangular metal frame constructed preferably from sections cut from stock bars of extruded metal of substantially the cross sectional pattern shown in Fig. 5, by mitering the ends of the bar sections and brazing or otherwise uniting 65 the meeting ends of bars to form a rigid metal frame as shown in Fig. 1. The bar sections of the frame 16 are preferably of angular or channel shape in cross section to afford rigidity in the finished frame compared with the weight of metal employed. They are also provided with a rib or ledge 17 forming an annular support for one face of the glass, and with a channel 18 along which the jaw engaging levers 19 and the glass supporting members 20 are adjustable and may 70 be spaced apart relative to the frame 16 previously to uniting the sections to form the frame 16. The channels 18 are preferably of cylindrical pattern, and are engaged by counter-part cylindrical sections 22 forming part of the members 19, and counterpart sections 24 forming part of the members 20, to thereby enable the members 19 and 20 to slide endwise in the channels 18, while the free ends of the members 19 and 20 have a limited amount of movement pivotally 75 about their sections 22 and 24, relative to the frame 16. Once the frame 16 is assembled the members 19 and 20 are not detachable from the frame 16. If desired, after the sections of frame 80 16 have been united, the members 19 and 20 may be adjusted to substantially the positions shown in Fig. 1 or to other desired positions and then members 19 and 20 locked against further adjustment endwise of the channels 18 by striking the edges of the channels 18 upon opposite sides of said members 19 and 20 with a center punch or other tool to distort the edges of the channel 18 at 25 and lock members 19 and 20 to the desired localities relative to the frame 16. The members 20 have dovetail recesses 26 adapted to receive blocks of rubber, fiber or similar material 85 27 upon which the lower edge of the glass is adapted to rest at two or more localities, depending upon the size of the plate of glass. Ordinarily two members 20, placed near opposite ends of the 90

110

bottom of the sash are sufficient to support the glass. The lower faces 28 of members 20 rest upon the inner face of the lower section of the frame 16. A number, two or more lever members 19 are spaced along each section or side of the frame 16. The sash 16 is set in the store front or other locality, and is ready to have the glass introduced upon the glass supporting members 20 and 27 from the outside of the sash.

10 The members 19 and 20 are produced by severing a stock bar of extruded metal into short sections.

15 A series of clamping jaw members 30, which are cut to the desired lengths from extruded metal stock bars of substantially the cross sectional pattern shown in Fig. 4, with their ends mitered, are introduced into place one after another with reference to the frame 16 and the glass and the members 19 and 20. The bar sections 30 are provided with an edge which rests upon or against the inside of the extreme edge 31 of the sash 16. The upper edge 32 of the sections 30 forms jaws which engage the outer face of the glass plate opposite to the jaw or ledge 17. The bars 30 are also provided with inwardly extending ledges 33 terminating in a cylindrical bead 34 which bead 34 is engaged in a recess 35 in the free end of each clamping lever 19 as the bar 30 is introduced into position relative to the frame 16. After a bar 30 has been adjusted to position, screws 38 threaded through perforations 39 in the frame 16 serve to engage the members 19 and to apply pressure to each member 19, intermediate of its section 22 and its section 35, to thereby cause the section 35 of each member 19 to bear upon the bead 34 and cause the bar 30 to turn where its edge 40 rests as a fulcrum upon the edge 31 of the frame 16, thereby causing the jaw 32 of the bar 30 to press against the outer face of the glass and to clamp the glass firmly between the jaw face 32 and the jaw face 17. The members 19 are preferably constructed to have sufficient resiliency so that when the screws 38 are tightened the jaw 32 will act with sufficient force to hold the glass in place without liability to pinch or fracture the glass. The members 19 are preferably provided with stop members 42, which ultimately contact with the inner face of the frame 16 to limit the strain applied by screws 38 to the jaw faces 32. The frame 16 is preferably provided with a channel 43 which being located inside of the glass serve to catch and drain away any water of condensation accumulating upon the inside of the glass. Each section or bar 30 is introduced independently, and if required may be independently detached and removed by loosening the screws 38. The frame 16 with members 19 and 20 attached is adapted to be shipped from the factory as a unit, and the bar members 30 are adapted to be compactly packed for shipment.

60 The apparatus herein shown and described is capable of considerable modification within the scope of the claims, without departing from the spirit of my invention.

65 What I claim is:

1. A sash comprising a rectangular frame member having a series of clamping levers spaced at intervals along the inside of said frame and having a limited movement pivotally relative to said frame, and a plurality of clamping jaw members of angular cross-sectional pattern each having a fulcrum engagement with said frame at the apex of its angle with one arm of the angle serving as a jaw to engage the outer face of a

glass, and the other arm of its angle engaged by said clamping levers, and means to force said lever members into engagement with the respective clamping jaw members to clamp the glass in position relative to its frame member.

80

2. A sash comprising a plate of glass, a rectangular frame provided with an annular ledge to engage one side of said glass plate and with means to support one edge of said plate relative to said frame, a plurality of independently adjustable clamping jaw members of angular cross-section having fulcrum engagement with said frame and adapted to respectively hold sections near the edge of said plate in contact with the ledge of said frame, lever members pivotally attached to said frame at one end and in engagement with said clamping jaw members near their opposite ends adapted to force said clamping jaw members into engagement with said plate, and means to apply power to said lever members to actuate said lever members.

85

90

3. A sash comprising a plate of glass, a rectangular frame provided with an annular ledge to engage one side of said glass plate and with means to support one edge of said plate relative to said frame, a plurality of independently adjustable clamping jaw members seated on the frame within the body lines thereof and adapted to respectively hold sections near the edge of said plate in contact with the ledge of said frame and means attached to said frame and operatively engaging said clamping jaw members to clamp said glass plate between the ledge of said frame and said clamping jaw members and to hold the clamping jaw members on the top of said frame.

110

4. A sash comprising a plate of glass, a rectangular frame provided with an annular ledge to engage one side of said glass plate and with means to support one edge of said plate relative to said frame, a plurality of independently adjustable clamping jaw members each having fulcrum engagement on the inner associated faces of the frame and adapted to respectively hold sections near the edge of said plate in contact with the ledge of said frame and spaced lever members engaging said frame and said clamping jaw members and operable in pairs to clamp said glass plate between the ledge of said frame and said clamping jaw members.

115

5. A sash comprising a plate of glass, a rectangular frame provided with an annular ledge to engage one side of said glass plate and with means to support one edge of said plate relative to said frame, a plurality of independently adjustable clamping jaw members having fulcrum engagement with the inner faces of the frame and adapted to respectively hold sections near the edge of said plate in contact with the ledge of said frame and means located between said frame and said clamping jaw members and outside of the limits of said plate operatively engaging said clamping jaw members to clamp said glass plate between the ledge of said frame and said clamping jaw members.

120

6. In a sash member the combination of a frame section having a ledge to engage one face of a glass plate, and a groove, glass supporting members resting on said frame and having the ends thereof extending into said groove, lever members pivoted at the ends in said groove and having near their opposite free ends transverse downwardly opening grooves, a clamping jaw member seated on said frame member, an inwardly extending ledge member on said jaw member, a groove in said lever member receiving

125

130

135

140

145

150

the ledge of the jaw member, and means adjustable from the exterior of the frame for pressing on the pivoted members intermediate their ends.

7. In a sash construction the combination of a rectangular frame comprising extruded strips each grooved on an inner face, clamp extruded jaw strips having inwardly extending ledges opposite the grooves on the frame, levers com-

prising short sections of extruded metal pivoted at one end in said grooves and engaging said ledges at the opposite end, and screw members for pressing the levers downwardly to clamp the jaw members to the frame members whereby to hold a glass plate between said jaws and frame.
